UNITED STATES PATENT OFFICE.

FELICJA GRINOCH, OF NEW YORK, N. Y.

DESIGN FOR A LADY'S COLLAR.

51,590.

Specification for Design.

Patented Dec. 18, 1917.

Application filed November 2, 1917. Serial No. 199,969. Term of patent 3½ years.

To all whom it may concern:

Be it known that I, FELICJA GRINOCH, a citizen of the United States, and residing in the city of New York, county of New York, and State of New York, have invented a new, original, and ornamental Design for a Lady's Collar, of which the following is a specification, reference being had to the accompanying drawing, forming part thereof.

Fig. 2 a side view thereof.

I claim:—

The ornamental design for a lady's collar, as shown.

FELICJA GRINOCH.

Witnesses:

JACOB JAROLSON,
PAULINE GILBERG.
